UNITED STATES PATENT OFFICE.

PERCY RUSSELL, OF PHILADELPHIA, PENNSYLVANIA, AND ADOLPH W. SCHRAMM, OF RIVERTON, NEW JERSEY, ASSIGNORS TO ELECTRO DENTAL MANUFACTURING COMPANY, OF PHILADELPHIA, PENNSYLVANIA, A CORPORATION OF PENNSYLVANIA.

PRESSURE-REGULATOR.

1,257,741.

Specification of Letters Patent. Patented Feb. 26, 1918.

Application filed December 2, 1916. Serial No. 134,615.

To all whom it may concern:

Be it known that we, PERCY RUSSELL and ADOLPH W. SCHRAMM, citizens of the United States, residing in Philadelphia, county of Philadelphia, State of Pennsylvania, and Riverton, Burlington county, State of New Jersey, have invented certain Improvements in Pressure-Regulators, of which the following is a specification.

One object of our invention is to provide a device for automatically delivering fluid, such as compressed air, at a substantially uniform pressure from a source whose pressure varies, the arrangement of parts being such that the apparatus closely governs the pressure between the predetermined limits.

We further desire to provide a regulator of the type above noted, with a readily removable valve unit and of such construction that easy access may be had to its interior without the necessity for disconnecting the supply or delivery pipes.

Another object of our invention is to so arrange and construct the parts of the regulator that its operating handle or knob may be easily turned, although being effectually prevented from operation in either direction beyond predetermined limits;—the handle and its associated parts being so made that it projects but a relatively short and constant distance beyond the surface of the structure on which it is mounted regardless of the position of the valve which it controls.

We also desire to so mount the several parts associated with the valve and its operating handle that a blow on said handle will not injuriously affect the device, whose design is such as to permit of its adjustment to supporting structures, such as marble slabs or switch boards, of widely varying thickness.

These objects and other advantageous ends we secure as hereinafter set forth, reference being had to the accompanying drawings, in which,

Figures 1 and 2 are respectively a side elevation and a plan of a pressure regulator constructed according to our invention;

Figs. 3 and 4 are respectively an inverted plan and a plan of the regulator after the bottom and the cover plate with the diaphragm have been respectively removed;

Figs. 5 and 6 are respectively perspective views of the body and cover plate;

Fig. 7 is an enlarged vertical section of the regulator shown in Fig. 1;

Figs. 8 to 10 inclusive are perspective views of details of the invention; and

Fig. 11 is an inverted plan of the nut shown in Fig. 10.

In the above drawings 1 represents an annular body in the form of a casting having an inlet connection 2 and two outlet nipples 3. Said connection has screwed on it a cap 4 having a threaded nipple 5 and confines a pair of thin screens 6 and 7 in place over the end of the passage through the conduit 2. As shown in Fig. 7, this conduit continues into the hollow of the body 1 and terminates (Fig. 5) in a plane face inclined at an acute angle to the line of the passage 8, being countersunk concentrically with the end of said passage for the reception of a projecting nipple 9 at one end of a relatively thick plate 10 whose ends are curved to fit into the body 1. Said plate has a hole 11 extending between its faces and also has leading from said nipple 9 a passage 12 which opens on its under face concentrically with a valve seat 13 projecting beyond the plane of said face.

As shown in Fig. 3, the plate 10 is held to the annular body 1 by a pair of screws 14 which pass through it at one end in lines inclined at an acute angle to its plane, and are threaded into the inclined portion 15, Figs. 4 and 5, of said body on opposite sides of the opening of the passage 8. A T-shaped piece 16 (Fig. 9) constituting a valve arm is mounted substantially parallel with and adjacent the plate 10 and at the extremity of its central member carries a valve 17 in position to coact with the valve seat 13 so as to regulate the flow of air through the passages 8 and 12.

The end member of this valve arm 16 is longitudinally slotted for the reception of a

spring plate 18 which is riveted in place and is clamped to the face of a raised shoulder 19 at that end of the plate 10 distant from the valve seat 13, there being screws, of 5 which one is shown at 20, passing through said plate and through openings 21 in the hinge spring 18 into a clamping block 22. It is to be particularly noted that the face of the valve 17 and the hinge spring 18 lie 10 in the same plane and that the edge of the clamping block 22 engaging the hinge spring 18 adjacent the arm 16 is straight and sharp. The movement of said valve arm 16 with its valve 17, away from the plate 10 is limited 15 by a stop screw 24 which passes through said arm into said plate and in order to prevent chattering or whistling of said valve we mount a spring piece 25 between the under side of the head of the screw 24 and the 20 plate 10 so as to exert friction upon said parts sufficient to prevent objectionable vibration of said valve.

The bottom face of the body 1 is normally closed by a circular plate 26 held in place by 25 a suitable number of screws 28 and the opposite face of said body is similarly closed by a cover plate 27 engaged by the same screws which pass through said first cover 26. This latter is provided with an annular 30 recess for the reception of a flange 29 on the body 1 and the cover plate 27 is formed with a similar flange 30 designed to fit an annular recess in said body. Between this latter flange and the adjacent face of the 35 body is confined a flexible diaphragm 31 carrying at its middle a stud 32 having a threaded stem passing through it and clamped in place by a nut 33.

This stud projects downwardly through 40 the opening 11 in the plate 10 into engagement with a screw 34 adjustably threaded through the valve arm 16 and it is noted that said screw and stud engage each other at a point lying within or immediately adjacent 45 the plane which includes the hinge spring 18 and the face of the valve seat 13. A sleeve 35 is threaded into the cover plate 27 concentrically with the stud 32 and extends through a suitable opening in a marble slab 50 36 or other suitable supporting structure, the outer end of this sleeve being likewise threaded for the reception of a collar or escutcheon 37. As shown in Fig. 6, the passage through the sleeve 35 is polygonal in 55 section and is designed to provide a guide-way for the flange 38 of a nut 39 so as to hold this from turning while permitting its longitudinal movement.

A coiled spring 40 is mounted within the 60 sleeve 35 between the clamping nut 33 and the flange 38 of the nut 39 whose position may be varied by means of a stem 41 passing through it and formed with a thread co-acting with a thread in said nut. This stem 65 has on its upper end a flange 46, and a cy-

lindrical portion 42 terminating in a threaded extremity 43. On this extremity is mounted a knob or handle 44 held in place by a set screw 45, and between said handle and the flange 46 is a ring 48 threaded into 70 the escutcheon 37 and having an inwardly projecting flange confining an anti-friction bearing 47 against the flange 46.

With the above described arrangement of parts the regulator may be fitted to a marble 75 or other supporting structure 36 with the utmost ease, since the retaining ring 48 and sleeve 35 together form a threaded structure of constant length upon which the escutcheon 37 is adjustable toward and from 80 the cover 27. In any case said sleeve with its attached parts may be clamped in place on the slab 36 merely by adjusting the escutcheon or collar 37 which likewise holds the retaining ring 48 tightly against the end 85 of the sleeve.

If the inlet nipple 5 be connected to a source of compressed air such as a tank, the air under pressure will normally be prevented from escaping into the interior of 90 the annular body 1 and thence to the outlets 3, since the hinge spring 18 acts to hold the valve 17 in engagement with its seat 13. If however, the handle 44 be so turned as to move the nut 39 downwardly upon the 95 spindle 41, the spring 40 is compressed and caused to exert pressure upon the stud 32 and hence upon the screw 34 and valve arm 16, the amount of such pressure being dependent upon the position of said nut. When this 100 pressure has been increased sufficiently, the valve 17 is moved away from its seat and permits the high pressure air to enter the hollow of the body 1 and pass to the outlets, as well as act upon the diaphragm 31 in 105 opposition to the downward pressure exerted by the spring 40. When the pressure of said air in the body rises to a predetermined point, the diaphragm yields against the action of the spring 40 so that the hinge spring 110 18 moves the valve 17 to its closed position and holds it closed until the pressure has so far fallen because of the flow of air to the outlets, that the diaphragm 31 is forced down by the spring 40. This causes the 115 stud 32 to act on the arm 16 and move the valve away from its seat so as to permit a further inflow of air.

In any case, however, the pressure actually existing in the body and supplied to the 120 outlets is maintained constant between certain predetermined limits depending upon the position to which the nut 39 is moved by rotation of the handle 44. Moreover, this pressure in the body is substantially independent of the pressure at which the air is delivered from the source, so that even though this be comparatively high when the device is first put into operation and though it thereafter falls as the air is used, the pres- 125 130

sure of the air delivered from the regulator remains constant between the predetermined narrow limits.

A valuable feature of the invention resides in the fact that the knob or handle 44 remains at the same distance from the adjacent face of the slab 38 regardless of the position of the nut 39 and of the adjustment of the valve 17, so that it obviously is not open to the objection of projecting a considerable distance beyond the slab when the valve is open. In order to prevent the stem 41 being run out of the nut 39, its lower end has a lateral projection, as indicated at 50, so that it projects and will engage a projecting shoulder 51 on the lower end of said nut when the stem has been screwed out to the desired extent. Obviously the travel of the nut in the opposite direction is limited 20 by the flange 46.

By providing the antifriction bearings as shown, the turning of the handle or knob is made easy regardless of the pressure of the spring 40 and by reason of the arrangement 25 and structure of the parts associated therewith, no damage is caused to the mechanism within the body 1 by reason of an accidental blow on the knob, such as might occur in shipping.

By practical experience we have found that by placing the fine screens 6 and 7 in the inlet conduit immediately adjacent the valve, slight particles such as scale, dust, etc., are very effectually kept from lodgment 35 on the valve or its seat. It will be understood that this is of vital importance since the device and the valve itself are relatively small in size and even a minute particle of dust or other small body of solid material 40 between the valve and its seat would injuriously affect the operation of the regulator.

By reason of the peculiar mounting of the valve 17 and its associated supporting and coacting structures, we insure that the 45 minute movement of said valve in opening or closing occurs in a line which to all intents and purposes is perpendicular to the plane of the valve seat 13. As a result, wear of the valve is reduced to a minimum, so 50 that even after long continued use there is no leakage past it nor material depreciation of its working face.

The arrangement of the above noted parts is such as to limit the movement of the arm 55 and therefore the flexing of the spring 18 to an amount such as not to overstrain said spring. Moreover, lateral motion of said arm is prevented and there is nothing to interfere with the proper engagement and 60 tight fit of the valve at all times.

We claim:—

1. The combination of a casing having an inlet and an outlet for fluid under pressure; a valve; a spring hinge normally tending to cause the valve to close the inlet; yieldable

means for exerting an unseating force on the valve; and a pressure actuated device mounted to oppose action of said means.

2. The combination of a casing having an inlet and an outlet for fluid under pressure; 70 a valve; a member carrying the valve; means operative on said member and normally tending to actuate the valve to close the inlet; a diaphragm mounted in the casing and operatively connected to the valve; a manually operative screw also operatively connected to the valve; a friction member interposed between said screw and the valve; and a stop operative on said valve carrying member to prevent its excessive displacement. 80

3. A pressure regulator consisting of a casing having within it an inlet conduit terminating in an inclined face; a structure in the casing having a passage terminating in a valve seat and connecting with said inlet 85 conduit; an arm movably connected to the structure; a valve carried by the arm in position to coact with the valve seat; and means operative on the arm for governing the passage of fluid under pressure from the 90 inlet into the casing, said structure with the arm and valve being removable as a unit from the casing.

4. The combination of a casing having a cover and formed with an inlet conduit 95 terminating in a surface inclined to its general plane; a member having a portion fitting said surface and removably mounted in the casing, there being a passage in said member forming a continuation of the conduit and terminating in a valve seat; a valve movably carried by said member and coacting with said seat; and means for governing the operation of said valve.

5. The combination of a casing having 105 within it an inlet conduit terminating in an inclined surface; a plate having a passage forming a continuation of said conduit and fitted to said inclined surface; means for removably connecting said plate to the casing 110 structure; a valve in the casing controlling the flow of fluid through said conduit and passage; and means for controlling said valve.

6. The combination of a casing having an 115 inlet and an outlet; a member mounted within the casing and having a passage forming a continuation of the inlet; a spring strip fixed to the member; an arm mounted on the strip; a valve carried by the arm and 120 normally held by said spring strip in position to close the passage in said member; with means operative on the arm for controlling the valve.

7. The combination of a casing having an 125 inlet and an outlet; a member mounted within the casing and having a passage forming a continuation of the inlet; a spring strip fixed to the member; an arm mounted on the strip; a valve carried by the arm and nor- 130

mally held by said spring strip in position to close the passage in the member; means operative on the arm for controlling the valve; and a member for preventing chatter-
5 ing of the valve.

8. A pressure regulator including a casing having a projecting sleeve; a second and independent sleeve forming a continuation of said first sleeve; a retaining collar threaded on said sleeves for separably connecting the same and clamping said casing to a supporting structure; and means operative through the sleeves for controlling the regulator.

15. 9. A pressure regulator including a casing having a projecting sleeve; a second sleeve in line with said first sleeve; controlling mechanism for the regulator including a spindle passing through said sleeves; a handle for the spindle operative adjacent the second sleeve; and a retaining collar adjustably threaded on the external surfaces of the sleeves and separably connecting the same.

25. 10. The combination of a casing having an inlet and an outlet; a perforated member mounted in the casing; an arm mounted on said member in the casing and including a part operative to normally close the inlet; a stud projecting through the perforation in
30 the member into engagement with the arm; and means acting on said stud to unseat the valve at will.

35. 11. The combination of a casing having an inlet and an outlet; a perforated member mounted in the casing; an arm mounted on the member and including a part operative to normally close the inlet; a stud projecting through the perforation in the mem-

ber into engagement with the arm; manually controlled means operative on the stud 40 for unseating the valve at will; and fluid pressure actuated means also operative on the stud to oppose said first means.

12. The combinatiton in a pressure regulator of a casing having an inlet and an outlet for fluid under pressure; a removable structure mounted in the casing having a passage forming a continuation of the inlet; a spring strip clamped to said structure; an arm carried by said strip; a valve mounted 50 on said arm in position to close said passage; and mechanism removably engaging the arm for unseating the valve at will.

13. The combination of a casing having an inlet and an outlet for fluid under pressure; 55 a diaphragm in the casing; a stud carried by said diaphragm; a plate in the casing having an opening for the passage of said stud and provided with a passage connected to the inlet; an arm movably mounted on said plate; 60 a valve carried by the arm in position to control the flow of fluid through the passage into the casing; a screw mounted in the arm and engaging the stud; with mechanism 65 operative on the diaphragm for unseating the valve at will.

14. The combination in a pressure regulator of a casing; a diaphragm; a stud carried by said diaphragm; a plate having an opening for the passage of the stud; an arm mov- 70 ably mounted on the plate; a screw carried by the arm and engaging the stud; and a valve also carried by the arm for controlling the flow of fluid into the casing.

PERCY RUSSELL.
ADOLPH W. SCHRAMM.
